UNITED STATES PATENT OFFICE.

ALFA LOMAX, OF ATLANTA, GEORGIA.

PHOTOGRAPH-CLEANING DEVICE.

1,346,662.

Specification of Letters Patent.

Patented July 13, 1920.

Application filed December 11, 1919. Serial No. 344,005.

To all whom it may concern:

Be it known that I, ALFA LOMAX, a citizen of the United States, and resident of Atlanta, in the county of Fulton and State 5 of Georgia, have invented certain new and useful Improvements in Photograph-Cleaning Devices, of which the following is a specification, reference being had therein to the accompanying drawing.

10 In ordinary photography, fixing and toning baths leave upon the prints a deposit which it is very difficult to remove if the print be permitted to dry, and which is not removed by such washing in running water 15 as will remove the chemicals which are ordinarily eliminated. It is, therefore, common to "mop" the prints manually, using some fibrous or soft material which will not injure the print. This is a slow and disagreeable process, the hands being immersed 20 in water and usually cold water, and it requires both care and skill.

The object of this invention is to mop the prints safely, rapidly and effectually, without 25 unpleasant operations of any kind. The desired end is reached by passing the prints under soft moving brushes which act while the print is supplied with a liberal amount of water discharged near the brushing 30 points.

In the accompanying drawings,

Figure 1 is a plan view of the apparatus.

Fig. 2 is a side elevation of the same.

Fig. 3 is a vertical longitudinal section 35 of the same devices.

In these drawings, 10 represents a metal frame supporting all the working parts of the apparatus, 11 a metal tank removably mounted in the frame, 12 an endless print-carrying belt mounted on rollers 13, 14 and made in any suitable way, as by placing an endless band of felt upon an endless perforated belt of rubber reinforced by textile threads, the belt being without novelty 40 herein claimed. The roller 13 is driven by gearing 17 actuated either by a crank 25 or a power belt 26. Upon the middle portion of the frame, above the belt are mounted 45 mopping rollers 27 actuated by gears 28, 29, 50 30, which rotate them in the same direction and are themselves driven by a chain belt 31 from the shaft of one of the gears 17. These mop rollers are covered with soft textile material or the like, and arranged to 55 run in contact with the endless belt which

at this point is supported by a rigid bar or plate 32.

On each side of the two mop rollers and between the two are heavy vertically movable print-retarding rollers 35, preferably 60 covered with rubber and serving to hold the prints while they are acted upon by the more rapidly moving surfaces of the mop rollers under which the endless belt slowly carries them. Above the lower sides of the 65 same are terminally closed water pipes 34, supplied from a pipe 39 and laterally perforated to deliver water downwardly toward or upon the mop rollers, so that as the rollers act upon the prints there is a copious 70 supply of water constantly changed at the mopping point and serving to remove sediment as fast as it is loosened from the surfaces of the prints and carry it down into the tank. 75

The roller 14 is carried by arms 40 pivoted at 41 to swing from locked position slightly below a horizontal line through its pivot to the position shown in dotted lines. In the latter position, free access to the tank 80 is permitted. A spring 42 urges the roller forward when it is in the other position and keeps proper tension upon the belt.

Since the prints may adhere to the belt 85 slightly, a rather stiff brush 45 is mounted at the turn of the belt protected by a shield 46, above and so rotated by the gearing 17 as to brush the prints upward at this point, if they chance to adhere, and aid in discharging them from the machine. 90

Obviously, the water discharged by the pipes will pass through and off the margins of the foraminous belt, falling into the tank from which it may be discharged in any suitable way, as by a pipe 47. 95

What I claim is:

1. In apparatus of the class described, the combination with an approximately horizontal traveling belt adapted to advance photographic prints laid thereon, of a soft 100 print mop arranged above the belt to press gently upon prints passing upon the latter, and means for discharging water continuously upon the prints being acted upon.

2. The combination with an approximately horizontal print-carrying endless belt, of mop rollers above the belt arranged to make contact with prints passing on the latter, means for discharging water upon the prints being acted upon, means for 110

gently holding the prints against displacement by the mop rollers, and means for imparting movement to both belt and mop rollers.

- 5 3. The combination with a supporting frame and an open tank therein, of an endless foraminous belt mounted on the frame above the plane of the tank, mop rollers supported above and normally osculating with the belt's surface, water pipes arranged to discharge water upon the belt as it passes beneath the mop rollers; and means for simultaneously advancing the belt and rotating the mop rollers.
- 10 10 4. The combination with a frame supporting an open tank, of an endless horizontal belt arranged above the tank, mop
- 15

rollers above the belt and arranged to make contact with prints passing upon the latter, means for discharging water upon the prints 20 at the mop rollers, means for gently lifting the margins of the prints from the belt at the point where the latter turns downward after passing the mop rollers.

5. The combination with a frame, a tank 25 therein and an endless horizontal belt running upon parallel rollers near the upper side of the tank, one of said rollers being carried upon arms pivoted to swing upward with the belt to facilitate access to the tank. 30

In testimony whereof I hereunto affix my signature.

ALFA LOMAX.
